(57) **CLAIM**

The ornamental design for front panel for information technology automation appliance, as shown and described.

DESCRIPTION

FIG. 1 is a front-side perspective view of a front panel for information technology automation appliance according to the present invention;

FIG. 2 is a front view thereof;

FIG. 3 is a rear view thereof;

FIG. 4 is a top view thereof;

FIG. 5 is a bottom view thereof; and,

FIG. 6 is a side view thereof.

The broken lines shown in the figures described above are for illustrative purposes only and form no part of the claimed design.
